UNITED STATES PATENT OFFICE.

JOHN H. SHIPLEY, OF CLEVELAND, OHIO, ASSIGNOR TO THE CLEVELAND FOLDING MACHINE COMPANY, OF CLEVELAND, OHIO, A CORPORATION OF OHIO.

PAPER-FOLDING MACHINE.

Application filed October 8, 1923. Serial No. 667,204.

My invention relates to paper-folding machines, and more particularly to the transverse feeding frame thereof. The object of this invention is the provision in a paper-folding machine of a transfer appliance between the horizontal and vertical folding rolls which is less liable to become clogged with crumpled signatures and which may be more readily cleared therefrom than is any 5 appliance of this sort in the prior art.

Owing to the difficulty of obtaining complete coaction between the initial sets of folding rolls and the right-angle transfer mechanism of a paper-folding machine, difficulty 15 not infrequently is experienced through the piling up of signatures in the transfer frame, whereby it becomes jammed and the crumpled signatures are so tightly packed therein that the frame must be taken out of the 20 folding machine and dismantled in order to clear it of the tightly packed paper. This necessarily involves considerable delay and expense which the present invention successfully obviates.

25 In accordance with my improvements the transfer frame preferably is pivotally mounted adjacent to its lower edge within the paper-folding machine and a section thereof is movably mounted to insure better 30 operation and permit the ready removal of any signatures that may accidentally become jammed in said frame.

The details of this construction and advantages of its operation may be more readily 35 explained in connection with the accompanying drawings, wherein:

Figure 1 is a transverse sectional view of 40 a paper-folding machine equipped with my improvements and illustrating the right-angle feeding mechanism in elevation.

Fig. 2 is a fragmentary view in longitudinal section illustrating the right angle feeding mechanism positioned for use and its released position for clearance in dotted lines, 45 and

Fig. 3 is an enlarged transverse section through said right-angle feeding mechanism or frame centrally broken away.

Throughout the several figures of the 50 drawings I have employed the same character of reference to indicate similar parts.

Referring initially to Fig. 2, the folding and buckling rolls, *a*, *b*, *c* and *d* are shown in association with the throats of their co- 55 acting folding plates *e* and *f*, rearwardly

broken away. From the rolls *c*, *d* the signature passes immediately to the rolls *g*, *h* for directing it into the right-angle transfer appliance which is the construction herein specifically claimed.

Said appliance comprises a frame *i* pivoted at *i'* within the folding machine to swing through an arc approximately of 80° from the full line to the dotted line position; being held in its operative position by means of the links *i''* and thumb nuts *i'''*. The frame is provided with a series of rods *j'* rigidly mounted beneath the throat member *j* and an opposing series of rods *k'* resiliently supported, together with the throat member *k* by means of the coiled springs *k''*, as well shown in Fig. 3. From this, it will be understood that the right-hand section of the throat is yieldingly mounted in a manner to improve the operation of said transfer appliance by affording it a slight resilience. Moreover, since the entire spring-mounted member may be depressed against the tension of the springs, any jamming of crumpled signatures accidentally occurring below the 60 rolls *g*, *h*, will be localized at the throat member *k*.

When this accidentally occurs, it is extremely easy to remove the mass of signatures merely by releasing the links *i''* and 65 tilting the frame into its dotted line position of Fig. 2. For this purpose the main frame of the folding machine is of rearwardly open type as indicated in Figs. 1 and 2 in order to permit access to the downwardly tilted transfer appliance. As the frame is made readily yielding, the crumpled paper does not become so tightly jammed as is the case with ordinary folding machines not equipped with my improvements, while no disassembling of any portion of the machine is necessary 70 in order to free it of the accumulated signatures.

The grooved guide *l* provided for the right-angle transfer appliance is made vertically adjustable and is held in any adjusted position by the clamping screws *l'*. At the right of said guide there are provided one or more paired rolls *m*, *m* between which the lower edge of the signature passes 75 in order to impel it toward the right and effect a right-angle fold in the lateral folding plate *n*, shown broken away in Fig. 1.

Although I have illustrated the conical coiled springs *k''* for resiliently supporting 80

the movable section of the frame and throat, I do not desire to be limited as to the means for retaining them in normal operative relation with the stationary section.

- 5 Having now described a paper-folding machine equipped with the improvements of my present invention, which, however, is subject to more or less variations to adapt it for different classes of machines, I claim as new 10 and desire to secure by Letters Patent, together with such modifications as may be made therein by those ordinarily skilled in the art, the following:
1. The combination with a paper-folding machine, of a transfer appliance having relatively movable members, and resilient means

associated with said movable members for normally checking their relative movement, substantially as set forth.

2. The combination with a paper-folding machine having horizontal and vertical folding mechanisms, of an interposed transfer appliance comprising a frame having relatively movable throat members, and yielding means associated with the movable throat member adapted to retain it in operative relation against such relative movement, substantially as set forth.

In testimony whereof I do now affix my signature.

JOHN H. SHIPLEY.
